UNITED STATES PATENT OFFICE.

ROBERT W. PAIN, OF NEW YORK, N. Y., ASSIGNOR, BY MESNE ASSIGNMENTS,
TO THE MECHANICAL ORGUEINETTE COMPANY, OF SAME PLACE.

MECHANICAL MUSICAL INSTRUMENT.

SPECIFICATION forming part of Letters Patent No. 356,422, dated January 18, 1887.

Application filed December 3, 1884. Serial No. 149,366. (No model.)

To all whom it may concern:

Be it known that I, ROBERT W. PAIN, of New York, in the county and State of New York, have invented a certain new and useful 5 Improvement in Mechanical Musical Instruments, of which the following is a specification.

I will describe a mechanical musical instrument embodying my improvement, and then 10 point out the various features in claims.

In the accompanying drawings, Figure 1 is a transverse vertical section of a mechanical musical instrument embodying my improvement. Fig. 2 is a plan of a part thereof. Fig. 15 3 is a perspective view of a mellowing-board used therein. Fig. 4 is a longitudinal section of a pneumatic motor comprised in it. Fig. 5 is a front view of a rest for a traveling music-sheet, and Fig. 6 is a transverse section 20 of this rest.

Similar letters of reference designate corresponding parts in all the figures.

A designates the case of the instrument. It may be of any suitable construction.

25 B designates one of a series of sound-producing devices, consisting of reeds arranged in cells *a*. The cells *a* communicate with a wind-chest, C, under control of valves D. The wind-chest communicates with an equalizer, 30 E, with which are combined bellows F. The bellows F may be of any suitable construction. As here shown the bellows are suction-bellows. The equalizer E is, as usual, of bellows-like construction.

35 The valves D of the reed-cells are arranged in the wind-chest C. Each valve consists of a lever, which may be made of wood or analogous material, provided with a face of sheep-skin or like substance, *c*, and fulcrumed near 40 one end to a pin, *b*. It is preferably guided in its movements by a pin, *d*, extending through it. A spring, *e*, holds it normally in position to cut off communication between the reed-cell and the wind-chest.

45 Each valve D extends over a pneumatic motor, G, arranged in line with it in the wind-chest. The pneumatic motor consists of a strip of wood or like material fastened by a flexible material to the upper wall of the

wind-chest. At one end the strip of wood of 50 the motor is fastened close to the wind-chest. The motor is similar to an ordinary organ-bellows, only very much smaller. Its strip of wood swings on one end, and hence is similar to a lever fulcrumed at one end. The 55 valve D extends well over the strip of wood comprised in the motor.

From the pneumatic motors G ducts *f* extend to the apex of a rest, H. A perforated music-sheet, I, travels over the rest H and 60 controls the passage of air to the interior of the motors. These ducts *f* converge toward the middle of the rest as they extend upward; hence a music-sheet narrower than the range 65 of motors can be used.

When air is admitted to a pneumatic motor, the latter is expanded, and it then opens the valve D, with which it acts. On the entrance of the air a valve, *g*, consisting of a resilient strip of metal, is closed. When air is cut off, 70 the valve *g* opens and the air within the motor passes to the wind-chest.

In order to soften and mellow the sound of the reeds, I arrange a mellowing-board, B', over the fronts of the reed-cells. This mellowing-board extends up from the top of the wind-chest C and over the board in which the reed-cells are formed. The front of this board in which the reed-cells are formed is oblique, owing to the fact that the reed-cells are all in 75 80 line at the rear end, and only as long as is requisite to enable them to contain the different sizes of reeds which are used for different notes. I do not, however, make the upright portion of the mellowing-board parallel with 85 the front of the board in which the reed-cells are formed, but parallel with the rest H and front of the instrument-case. I have found this productive of the best results. An opening, *b'*, preferably located in the upright portion 90 of the mellowing-board, emits the sound. On the mellowing-board is an upwardly-extending rib, B''. The case A has a hinged cover, A', which, when shut down, rests upon this rib B''. It also has a hinged cover, A'', 95 which, when closed, rests against the front of the rib B''. Either cover of the case may be opened and closed at pleasure.

What I claim as my invention, and desire to secure by Letters Patent, is—

1. The combination, with the reed-cells of a musical instrument ending at an oblique line, 5 of a mellowing-board extending in front and over the forward end of the range of reed-cells and parallel with the front of the case, and having an opening opposite the ends of the reed cells, substantially as specified.

2. The combination of the mellowing-board 10 B', its rib B², and the covers A' A² of the case, substantially as specified.

ROBERT W. PAIN.
